(57) **CLAIM**

The ornamental design for a detachable crossbody zipper wallet phone case with wireless charging function and e-logo stand as shown and described.

DESCRIPTION

FIG. 1 is a perspective view of a detachable crossbody zipper wallet phone case with wireless charging function and e-logo stand, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded perspective view thereof in which the detachable zipper wallet component and the phone case component are shown separated for clarity of disclosure.

The detachable crossbody zipper wallet phone case with wireless charging function and e-logo stand is shown with a symbolic break in its length. The appearance of any portion of the detachable crossbody zipper wallet phone case with wireless charging function and e-logo stand between the break lines forms no part of the claimed design.
